Filed July 1, 1968, Ser. No. 12,561

Term of patent 14 years

Int. Cl. D23—01

U.S. Cl. D23—6

FIG. 1 is a perspective view of a water sprinkler bath toy showing my new design;

FIG. 2 is a side elevational view thereof, the hose being broken away for convenience of illustration;

FIG. 3 is an enlarged fragmentary perspective view of the spray head;

FIG. 4 is an enlarged fragmentary perspective view of the faucet attachment end;

FIG. 5 is a reduced scale perspective view thereof; and

FIG. 6 is another reduced scale perspective view thereof.

The broken line showing of a bathtub in FIG. 5 and a play pool in FIG. 6 is for purposes of illustration only.

I claim:

The ornamental design for a water sprinkler bath toy, as shown and described.
